Primary Examiner — Ruth McInroy(74) *Attorney, Agent, or Firm* — Rabin & Berdo, P.C.(57) **CLAIM**

The ornamental design for a bread maker, as shown and described.

DESCRIPTION

FIG. 1 is a front view of a bread maker showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken line showing in Figures is for illustrative purposes only and forms no part of the claimed design.
